ELECTRIC DISCHARGE DEVICE AND
METHOD OF OPERATING SAMELeroy J. Buttolph, Grantwood, N. J., assignor to
General Electric Vapor Lamp Company, Ho-
boken, N. J., a corporation of New Jersey

Application May 12, 1933, Serial No. 670,772

4 Claims. (Cl. 176—45)

The present invention relates to electric gaseous discharge devices, and to a novel method and means for starting and operating the same.

The invention consists in a novel combination 5 of elements, and in a novel sequence of steps, as hereinafter set forth and claimed.

A particular object of the invention is to provide a novel discharge device of the liquid cathode type which may be operated in either of two 10 positions with the same operating characteristics. Another object of the invention is to provide means for operating an electric gaseous discharge lamp of the rectifying type with a minimum of auxiliary apparatus. A further object of my 15 invention is to provide a novel discharge device which is especially adapted for use in combination with this novel operating means. Still another object of my invention is to provide a novel means for starting a discharge in a mercury vapor arc 20 of the so-called high pressure type. Another object of my invention is to provide a novel method of operating electric gaseous discharge devices of the rectifying type. Still other objects and advantages of my novel invention will 25 appear from the following detailed specification or from an inspection of the accompanying drawing.

It is frequently desirable to operate the high pressure type mercury vapor arc lamps, such as 30 are in extensive use for therapeutic purposes, with the arc tube in either a horizontal or a vertical position, in order to better direct the light therefrom for particular purposes. As heretofore constructed, however, these devices have 35 ordinarily been limited by their structure to operation in but a single position, due to the fact that the flow of the liquid cathode incident to any change in position very materially alters the length of the arc path and thus radically changes 40 the operating characteristics of the device. I have now discovered that this difficulty may be overcome by using a mercury vapor arc lamp having an extremely simple structure of my invention. This novel lamp has a tubular cathode 45 chamber whose axis is at an angle of approximately 45° with that of the main arc tube, and hence rotation of the main arc tube through the desired 90° angle merely moves said cathode chamber between two symmetrical positions at 50 45° to the vertical, the length of the arc being virtually the same in either position, or at any position therebetween.

The amount of auxiliary apparatus which has 55 heretofore been employed in operating mercury arc lamps, as well as other types of lamps having

similar rectifying characteristics, such as those operating with a thermionic cathode, on alternating current has also been a disadvantage, due both to the high initial cost, and to the bulkiness and weight of this apparatus. I have now discovered that virtually all of this auxiliary apparatus, including the usual autotransformer, can be eliminated by utilizing a novel connection for the lamp, and by operating the lamp in a novel manner. According to my invention the two 10 anodes usually provided in a lamp intended for use with alternating current are connected directly to opposite sides of an alternating current line, and one side of said line is likewise connected to the cathode through an inductance. With this 15 arrangement the inductance not only performs the usual function of stabilizing the arc, but also stores energy during one half cycle and gives it up during the next half cycle, whereby full wave operation is obtained without the use of a transformer. 20

Heretofore these high pressure mercury vapor arcs have always been started by the cumbersome method of tilting the lamp until the mercury momentarily bridges the electrodes, the arc at 25 separation establishing the desired arc between the electrodes. Even this method of starting is unsatisfactory, for when the vapor pressure within the lamp is so high that the discharge has the characteristic stringy appearance of a so-called high pressure arc it is impossible to restart the arc by this method, in case of momentary failure, until the lamp has cooled for at least five minutes. I have now discovered that by 30 using a novel type of shifter or switch I can start 35 an arc virtually instantaneously in my novel lamp, whether hot or cold, by means of a high voltage surge, although heretofore exhaustive test has demonstrated that this surge starting method could not be successfully used in lamps of this 40 type. The novel shifter which is thus an essential feature of my novel structure is a switch having solid metallic contacts which operate within an extremely high vacuum, such as disclosed by Warren R. Walker in his Patent 1,984,505, granted 45 December 18, 1934. I have discovered that this type of switch, unlike those previously used, can be made to produce a voltage surge in the inductance of sufficient potential to restart an arc even when the pressure is so high that it can not be 50 started by the tilting method previously referred to. Furthermore mercury arc lamps having insufficient mercury therein to bridge the electrodes may now likewise be started in this novel manner, regardless of whether they are of the mer- 55

cury electrode or of the thermionic electrode type. Likewise this novel method of starting is effective with these mercury arc devices, whether they be operated on direct current, or with a simple 5 or rectified discharge on alternating current.

For the purpose of illustrating my invention I have shown a preferred embodiment thereof in the accompanying drawing, in which

Fig. 1 is an elevational view of my novel lamp, 10 together with a schematic diagram of my novel operating circuit therefor, the lamp being shown with the arc tube horizontal, and

Fig. 2 is a similar view, showing the lamp in its vertical operating position.

As shown in the drawing my novel mercury vapor arc lamp has an arc tube 1 of fused silica or the like into one end of which open two parallel anode chambers 2 and 2' which are substantially tubular in form and which lie close to each 20 other. A pair of inleads 3 and 3' of tungsten or the like are sealed into the ends of the respective anode chambers through a conventional graded joint, each of said inleads supporting on the end thereof an anode 4 and 4', respectively, of iron, 25 molybdenum, or the like of conventional form. Said anodes 4 and 4' are preferably arranged directly opposite each other. The tubular cathode chamber 5, which opens into the opposite end of the arc tube 1, extends away from said anode 30 chambers, the axis of said chamber lying in the plane determined by the axes of said anode chambers, but extending downwardly, away from the anode 4, at an angle of approximately 45° with respect to said axes. An inlead 6 of tungsten or 35 the like which is sealed into the end of the chamber 5 through a conventional graded seal makes contact with the mercury cathode 7 which extends to a point slightly below the level of the arc tube 1 when the lamp is in the position shown 40 in Fig. 1. With this construction the cathode 7 is virtually the same distance from the anodes 4 and 4' when the lamp is in either of the positions shown in Figs. 1 and 2, or in any position therebetween. A metal sleeve 8 is clamped about 45 the cathode chamber 5 with one edge thereof adjacent to the surface of the mercury 7.

The anode inleads 3 and 3' are connected to opposite terminals of any suitable source of alternating current, of say 110 volts potential. An 50 inductance 9 is connected between the cathode inlead 6 and one of said terminals, preferably the same terminal which is connected to the anode inlead 3'. This inductance is preferably 55 relatively large, as compared to the usual stabilizing inductances, so that it can absorb considerable energy. For example, in the case of a lamp operating on 110 volts with a root mean square current of 5.5 amperes I preferably use an inductance of the order of $\frac{1}{3}$ henry. The sleeve 60 8 is connected to the other terminal of said line, while a switch 10 which is normally closed but which is adapted to be magnetically opened by the inductance 9, is connected between said inductance and the same terminal as the sleeve 8. Said switch 10 is preferably a highly evacuated 65 switch with solid metal contacts, and is schematically shown in the form of the switch disclosed by Warren R. Walker in his Patent 1,984,505, granted December 18, 1934, which has 70 proved extremely effective in this novel circuit. In this switch the fixed contacts are bridged by a freely movable, magnetically operated bar 11.

In the use and operation of this novel apparatus, as soon as an alternating current potential 75 is applied thereto current flows through the in-

ductance 9 and the switch 10. The magnetic field thus produced about the inductance 9 causes the switch 10 to be opened, whereupon the collapsing magnetic field produces an extremely high voltage surge of at least several thousand volts which is impressed upon the cathode 7. If the polarity of the source is such that the anode 4 is negative at the instant the switch 10 opens the circuit this surge is not effective to start the discharge. Hence the switch 10 is allowed to reclose as soon as the inductance 9 is deenergized, thus again energizing said inductance and reopening switch 10 as before. If now the polarity of the source is such that the anode 4 is positive at the instant said switch 10 opens the ensuing voltage surge 15 makes the cathode intensely negative with respect to both of the anodes 4 and 4', and to the sleeve 8. A disruptive discharge thereupon occurs at said cathode, establishing a hot spot on the mercury surface and ionizing the gaseous atmosphere within the arc tube. If the anode 4 is still positive with respect to the cathode 7 at this instant the main discharge is initiated therefrom, and the current thus flowing again energizes the inductance 9, and thus causes the switch 10 to 20 be maintained in an open circuit position. At the end of the half cycle the anode 4 becomes negative, so that current can no longer flow therefrom to the cathode 7. The anode 4' is connected to the same side of the line as the cathode 7, and 25 hence it is obvious that the line potential is ineffective to maintain a discharge from said anode 4'. As the discharge current from the anode 4 begins to fall to zero, however, the magnetic field about the inductance 9 begins to collapse, 30 inducing a potential in said inductance which makes the anode 4' sufficiently positive with respect to the cathode 7 to produce a current flow of almost the same value as was flowing from the anode 4. This current slightly decreases during this half cycle, but due to the large energy storage in the inductance 9 this decrease is not enough to markedly affect the light emission from the tube, so that there is no observable flicker 35 therein, as there would be if this were a mere keep-alive circuit. As the anode 4 again becomes positive the discharge shifts thereto and the magnetic energy stored in the inductance 9 is again increased, this cycle being continued so long as the energy is applied. The discharge is thus 40 operated as a full-wave rectified discharge, despite the fact that energy is only drawn from the line on alternate half cycles. The use of this novel circuit is, of course, not limited to mercury vapor lamps, for equal advantages are obtained when 45 it is used with any other type of lamp, such as those with thermionic cathodes, which have similar rectifying characteristics.

Heretofore it has been impossible to restart mercury vapor arc lamps of any type in which the vapor pressure is so high that the discharge is markedly constricted or stringy, as distinguished from the diffuse discharge at low pressures, without a very considerable delay period of at least five minutes, during which the lamp cooled and the 55 vapor pressure thus decreased. This has been a considerable source of annoyance, for if even a momentary line failure chanced to occur during treatment of a patient, the irradiation was not only stopped, but could not be restarted for a 60 considerable period, of the order of at least five minutes. With my novel apparatus this difficulty has been overcome, for virtually instantaneous starting is now attainable at all times, irrespective of whether the lamp is at room temperature. This 65 70 75 80 85 90 95 100

is due to the fact that the novel switch 18, unlike the mercury shifters previously used, can interrupt the inductive circuit while the current is still very large. Thus approximately all of the energy stored in the inductance is available to produce the voltage surge, which now for the first time is of sufficient value to immediately restart the arc in a high pressure quartz lamp while it is still hot. As a result I now find it possible to immediately restart a high pressure mercury arc at a time when it could not be restarted by any of the methods heretofore available. As a result I am now able to produce for the first time an automatic, self-starting, continuously operating mercury arc irrespective of the vapor pressure attained therein during operation, thus doing away with starting by hand tilting and avoiding the five minutes' wait to restart consequent upon the interruption of operation of such lamps, as heretofore made and sold.

While I have illustrated by invention my reference to a particular embodiment thereof it is to be understood that it is not limited thereto, but that various changes, omissions, or substitutions, within the scope of the appended claims may be made therein without departing from the spirit of my invention.

I claim as my invention:

1. In combination, an electric gaseous discharge lamp of the rectifying type having an elongated arc tube, a cathode at one end thereof, and a pair of anodes at the opposite end of said arc tube, the paths from said cathode to said anodes being of unequal length, means to connect a source of alternating current between said anodes, and a

connection including an inductance between said cathode and the anode which is nearer said cathode.

2. In combination, an electric gaseous discharge lamp of the rectifying type having an elongated arc tube, a cathode at one end thereof, and a pair of anodes at the opposite end of said arc tube, the paths from said cathode to said anodes being of unequal length, means to connect a source of alternating current between said anodes, and a connection including an inductance between said cathode and the anode which is nearer said cathode, said inductance being sufficiently large to avoid visible flicker in the light from said lamp.

3. In combination, a mercury vapor arc lamp having an anode and a cathode, means to operate said lamp with a high pressure, constricted discharge, said means including an inductance connected to said cathode, means to energize said inductance independently of current flow through said inductance, said last mentioned means including a vacuum switch having electrodes of solid metal, and a sleeve about said lamp adjacent to said cathode, said sleeve being connected to the terminal of said switch which is remote from said inductance.

4. The method of starting an arc in a mercury vapor lamp which comprises applying potential between an anode and the cathode thereof, and then producing a voltage surge therein of sufficient potential to ionize the mercury vapor when it is at such a pressure that the discharge therein is of the constricted type.
